UNITED STATES PATENT OFFICE

2,630,823

MAIN VALVE FOR FIRE HYDRANTS

Robert H. Mueller and Earl E. Cline, Decatur,
Ill., assignors to Mueller Co., Decatur, Ill., a corporation of Illinois

Application June 27, 1947, Serial No. 757,600

11 Claims. (Cl. 137—283)

1 The present invention relates to fire hydrants generally of the type comprising a vertical barrel and shoe, with a hydrant valve positioned near the lower end of the barrel and capable of manual operation from above the barrel. Such hydrants include various arrangements of outlet nozzles adjacent the top of the barrel, as well as different types of lubricant baths effective to lubricate around the upper end of the valve stem and in and around the operating nut therefor.

In our copending application, Serial No. 718,752, filed December 27, 1946, the general type of a hydrant structure referred to is disclosed, and the preferred embodiment of the main hydrant valve is also disclosed in said application.

The principal object of the invention is to provide a main hydrant valve of improved design, and which is capable of being removed as a unit through the barrel of the hydrant and from the shoe thereof. Included in the above purpose, it is our intention to provide a design wherein not only the valve member, but also the valve seat may be removed with the valve stem, as previously referred to.

The several embodiments disclosed herein provide an annular non-ferrous metal bushing which is secured within the barrel at the lower end thereof, and which is interiorly threaded, the valve seat ring constituting a part separate from this bushing, and being exteriorly threaded so that it may be removed from the bushing when desired. Cooperating means are provided on the valve seat ring and the valve stem, in order to permit unthreading the valve seat ring from the bushing, in order to remove the entire valve assembly from the barrel by the simple operation of turning the valve stem with a wrench.

It is an important object of the invention to provide a valve assembly of the above type provided with effective means for draining the interior of the hydrant barrel when the main valve is moved to its seat, the drainage mechanism including means for automatically closing the drainage passages when the main valve member is moved from its seat.

In general, it is an important purpose of the invention to provide a simple yet durable assembly for the above purposes which will effectively prevent leakage of water from the interior of the hydrant. Particularly, the several designs disclosed include a novel arrangement of O-rings surrounding the outlets provided by the valve drainage ports, in order that adequate drainage may be had without any possibility of undesirable leakage of water from the hydrant.

2 It is also a purpose of the invention to provide a main hydrant valve construction having means for preventing undesirable disengagement of the valve stem from the valve member.

Various other objects and advantages of the invention will be apparent as the description herein progresses.

In the drawings:

Figure 1 is a vertical sectional view of the lower part of the hydrant barrel and shoe and of the main valve assembly positioned therein.

Figure 2 is a horizontal sectional view through the hydrant barrel taken along the line 2—2 of Figure 1.

Figure 3 is a partial vertical sectional view through the lower portion of the hydrant barrel and shoe taken at substantially right angles to the view of Figure 1, for instance, generally along the line 3—3 of Figure 2. In this figure, the main valve is shown in its open position.

Figure 4 is a horizontal sectional view through the valve stem, just above the drain valve seats, for instance, along the line 4—4 of Figure 1.

Figure 5 is a horizontal sectional view through the valve stem, taken along the line 5—5 of Figure 1.

Figure 6 is a horizontal sectional view through the valve stem, taken along the line 6—6 of Figure 1.

Figure 7 is a partial sectional view through the arms or webs of the valve seat member, showing the drainage ports and the relation of the drainage valve member or plate thereto.

Figure 8 is a vertical sectional view similar to Figure 1 of a modified form of the invention.

Figure 9 is a partial vertical sectional view, at right angles to that of Figure 8, but showing the main valve in its open position. Figure 9 is taken in the plane indicated by the lines 9—9 of Figure 10.

Figure 10 is a horizontal sectional view taken along the line 10—10 of Figure 8.

Figure 11 is a horizontal sectional view taken along the line 11—11 of Figure 8.

Figure 12 is a vertical sectional view taken along the line 12—12 of Figure 11, illustrating the construction of the main valve member.

Figure 13 is a horizontal sectional view through the valve stem, taken along the line 13—13 of Figure 8.

Figure 14 is a similar horizontal sectional view taken along the line 14—14 of Figure 8.

Figure 15 is a view similar to Figure 12, i.e., a vertical sectional view of the main valve member, but showing a modified manner for attach-

3

ment of the upper valve washer to the valve stem.

Figure 16 is a horizontal sectional view, further illustrating the method of attachment just mentioned, being taken along the line 16—16 of Figure 15.

In Figure 1, a substantially cylindrical hydrant barrel is shown at B, and it has a shoe E at its lower end, and a bonnet or hood at its upper end as shown in our copending application referred to, but not specifically disclosed herein.

As is well known in the art, the hydrant has a valve operating stem S, which operates a main valve member V in order to control the discharge of water from the side outlets or nozzles at the upper end of the barrel, and which are not shown in the drawings.

The barrel B is of appropriate diameter for insertion of the valve parts to be mentioned and described herein, and in the present embodiment, the barrel is formed of an upper section 10 and a lower section 12. These sections are detachably connected together by flanges 14 secured by frangible bolts 16. Similarly, the valve stem S comprises an upper section 18 and a lower section 20 which are detachably held together by a sleeve 22 bolted around the union of said sections. Such sleeves are now well known in the art, and they are sometimes provided with a weakened portion at a point where the ends of the two sections of the valve stems are presented to and slightly spaced from one another, permit the parts of the valve stem to separate without fraction. As is well known in the art, the flanges of the barrel sections, the ends of the valve stem sections, the weakened portion of the sleeve 22 and of the bolts 16 are all in horizontal alignment. When an object strikes the hydrant, it will break in the horizontal plane referred to, without material damage to the valve parts. The parts are capable of reassembly by merely replacing the sleeve and bolts.

The shoe E has the usual means 25 for connection with the main or source of water supply, and at its outer end it has a top central opening surrounded by an inwardly projecting flange 26, the top surface of the flange being flat in order to provide for engagement with the circular flange 28 of the hydrant barrel, which may be attached to the flange 26 by bolts as shown. The barrel of the hydrant is preferably made of cast iron, and at its lower open end, is provided with an inside circular recess 30. An annular non-ferrous metal bushing 32 is tightly pressed and secured in this recess, and said bushing is interiorly threaded adjacent its lower end in order to receive and secure an annular non-ferrous valve seat ring 34 which is exteriorly threaded adjacent its lower end as shown in Figure 1. The valve seat ring 34 has a central opening therethrough, which is defined by a downwardly presented and outwardly tapering valve seat 36.

It will be noted that the surface of the flange 26 around its opening extends inwardly a sufficient distance as at 37 to lie beneath the bushing 32 and to also serve as a limiting abutment for the valve seat ring 34 when it is threaded into the bushing 32. The shoulder thus formed at 37 serves to properly position the valve seat. The valve seat ring 34 comprises a lower annular portion which includes the valve seat 36 as just referred to, and an upper portion comprising a pair of radially directed legs or spiders 38 terminating in a central hub 40. The open space through the seat ring between the legs 38 is great enough to provide free flow of water when the valve is open, as is clear from an examina-

4

tion of Figure 3. The legs 38 need only be large enough to contain the hydrant drain passages to be referred to, and to support the central hub 40.

As best shown in Figure 4, there is a central vertical opening 41 through the hub 40, which is of polygonal form corresponding with the cross sectional form of the valve stem, thereby permitting vertical sliding movements of the valve stem, while restraining any rotation thereof during normal operation of the hydrant. The valve stem may be square in the cross section from the valve member or head, up to a ledge 42 as shown in Figure 1. The polygonal or square portion of the valve stem is designated 43.

Extending through each of the legs 38 are drain passages 44. The outer ends of these passages connect with an annular groove 45 in the outer wall of the valve seat ring. A number of spaced radial openings 46 extend through the wall of the bushing 32 and through the wall of the barrel and connect with the groove 45 in the seat ring. These openings are lined with brass ferrules.

The passages 44 turn in a vertical direction near their upper ends, and they open into a flat upper valve face or ground surface which forms the top of the central bushing 40. The open ends of the passages are enlarged and receive therein resilient washers 50 of rubber or the like which normally project above the ground valve surface of the hub 40. The washers 50 may be interiorly lined with brass ferrules to prevent collapse. The washers 50 are positioned to be engaged by a valve plate 52 slidably mounted on an elliptical portion 53 (Figure 6) of the valve stem above the shoulder 42. The valve plate 52 has an area and is of the general form shown in Figure 2 adapting it to overlie and cover the openings in the washer 50. It has a central opening which has the shape of the shaft portion 53 as is indicated in Figure 2. When the main valve is closed, as shown in Figure 1, the shoulder at 42 on the valve stem raises the drain valve plate 52 from its seat on the top surface of the central hub 40, thus permitting the hydrant barrel to drain through the passages 44 in the arms 38.

Above and below the annular groove 45 located at the lower ends of the passage 44 and around the outside wall of the valve seating ring 34, there are upper and lower annular sealing grooves 54 (Figure 3) which receive O-rings therein. The grooves 54 are square in cross section, whereas the O-rings are circular in cross section, whereby a tight seal is insured between the valve seat ring and the bushing 32 above and below the ports 46. Any fluid under pressure which would tend to escape would cause the O-rings to more tightly seal as is now well known in the art.

The main valve comprises a seat washer 55 of packing or similar material, preferably laminated in nature and held between a bottom metal washer 56 and a top metal washer 57, these parts being assembled and held in place by means of a nut 58 threaded onto the lower end of the valve stem. The top valve plate or washer 57 and the portion 43 of the valve stem may be cast of such as brass or bronze, and ribs 59 may be provided on the top of plate 57. The outer edges of these ribs serve to center the valve when it engages the seat, said edges being guided into the central opening through the valve seat ring.

By reason of the fact that the portion 53 of the valve stem and the opening through the drain valve plate 52 are of the same elliptical form,

when the valve V is pulled upwardly onto its seat, the shoulder 42 on the valve stem is displaced to a position somewhat above the top surface of the resilient washers 50. This shoulder thus lifts the drain valve member a slight distance above the openings through the washers to the passages 44 as illustrated in Figure 1, to permit drainage from the hydrant as referred to. When the valve stem is moved downwardly to open the main valve for flow of water therethrough, the lower edge of the collar 60 on the valve stem engages the plate 52 and forces it downwardly against the washers 50 to compress the same and to thus seal off the openings previously described, so that the hydrant body is closed except at its outlets when the main valve is open. The top face of the hub 40 and the lower face of the drain valve plate 52 may be ground to provide metal-to-metal sealing contact when the openings are thus closed.

Referring to Figure 1, when the main valve member is moved downwardly from its seat, the ledge 42 passes into the central opening through the hub 40 and the drain valve member 52 by its own weight engages the bushings 50 and thereby closes the drain outlets or passages.

Subsequent and further downward movement of the valve stem brings the lower end of the collar 60 into engagement with the drain valve member 52, as illustrated in Figures 3 and 7, and the rubber washers 50 are compressed until the valve member 52 makes a metal-to-metal contact with the top face of the hub 40, the engaging faces being appropriately ground to provide for metal-to-metal sealing contact when the drain openings are closed. The engagement of the collar 60 with the plate 52 and the engagement of the latter with the top surface of the hub 40 serves to limit the degree of opening of the main valve V.

The mechanism for operating the valve stem in accordance with the above description is disclosed in our copending application referred to, and the description need not be repeated herein.

In the event that it is necessary to remove the main valve or its stem, a wrench is applied to the upper square section of the valve stem and appropriate turning of this stem will unthread and remove the valve seat ring by reason of the polygonal portion 43 thereof, which passes through the polygonal opening in the hub 40 of the valve seat ring. Obviously, the valve member and its seat, together with the associated parts referred to, constitute a unitary structure capable of being shipped, installed, removed and replaced as a unit.

In Figures 8 through 16, a modification of a main valve assembly of the type described is disclosed, the hydrant barrel B being generally the same as that described in connection with the principal embodiment of the invention. The valve stem S is of appropriate polygonal form, for instance, of hexagonal cross section as shown throughout the various views. The bushing 64 for receiving the valve seat is clamped between the flanges 66 and 68 of the lower end 69 of the hydrant barrel and shoe E' respectively. Appropriate sealing washers are provided between the engaging parts as shown, along the lower surface of the flange 66 and on the depressed ledge 70 in the top face of the flange 68 of the shoe. This ledge encircles the top opening from the interior of the shoe.

The seating ring 64 has a central vertical bore therethrough which terminates at its lower end in an inwardly tapered stop face 72. This bore

is interiorly threaded above its stop face, as shown, and is adapted to receive the valve seat ring 74 which has corresponding engaging exterior threads. The valve seat ring is provided with a lower tapering end which contacts the stop face 72 of the bushing 64, thus limiting the degree of insertion of the valve seat ring. The valve seat ring has a central flow opening, which is defined by an inwardly tapering main valve seat 76, to be contacted by the main valve member as previously described. There are eight angular drain passages 80 which extend from the top face 82 (Figure 11) of the valve seat ring 64 to the outer vertical wall thereof, and the upper ends of these passages are fitted with rubber washers 84 of form and arrangement similar to the washers 50 previously described. These washers are hollow and project above the top face 82 of the valve seat member, and they may be provided with inside brass ferrules for support and rigidity.

The bushing 64 has an inside annular groove 86, and the lower ends of the passages 80 connect with this groove. Leading outwardly from the groove 86 at appropriate spaced points are outlet passages 88 which pass through the wall of the bushing 64 to discharge water draining from the hydrant between the flanges 66 and 68 of the barrel and shoe respectively. In order to provide an effective seal above and below the drain outlet passages, the valve seat ring is provided with circular grooves and O-rings as previously described, in its outer surface above the passage 80 and in its lower tapered end surface below the passage 88.

The main valve member is composed of parts similar in design and material to those described in connection with the principal embodiment herein. There is a lower valve part or nut 90 and an upper brass valve part 92, and clamped between these parts are the valve packing rings 94 (Figure 12). The parts are clamped together by action of the lower cylindrical threaded end 96 of the valve stem onto which is threaded the lower nut 90 as at 97.

The lower portion 98 of the valve stem S is hexagonal in form down to the ledge 99, where it merges with the reduced lower threaded end 96 of the valve stem. There is a collar 100 pinned onto the valve stem portion 98 at a point spaced above the valve member, as shown in Figures 8 and 14. Below this collar, and loosely arranged on the valve stem, is a sleeve 101 of hexagonal form (Figure 10). This sleeve engages the collar 100 at its upper end, and is arranged so that its lower end, and the corners thereof, will abut the top edge of the boss 93 on the upper valve part 92 when the nut 90 is threaded onto the lower end of the valve stem. The boss 93 has an interior cylindrical bore of diameter to embrace but slide on the lower cylindrical end 96 of the valve stem.

The lower valve part has a central upwardly projecting cylindrical wall 102, around which the packing rings 94 are placed, and this wall has a cut-out 104 therein (best shown in Figure 15), into which projects a lug 106 (Figure 12) depending from the lower face of the upper valve part 92. By means of the locking action of the lug 106 and groove 104, both top and bottom parts of the valve member will turn together as the nut 90 is threaded onto the lower end of the valve stem at 96, and when the boss 93 contacts sleeve 101 (which is held at its upper end against collar 100) the upper valve part will be jammed

between the nut and sleeve and the packing 94 will thus be tightly compressed.

An appropriate set screw 108 may be provided through the upwardly extending boss 93 on the top valve part 92, to lock the upper valve part to the valve stem after the lower valve part is threaded home onto the valve stem as previously described.

In Figures 15 and 16 an alternative arrangement is shown for connecting the main valve parts to the valve stem. In this arrangement, the hexagonal portion 93' of the valve stem is of slightly increased length, extending substantially to the lower clamping face of the upper valve part 92. This valve part has an upwardly extending boss 93' (Figure 16) of cylindrical form large enough to slide over the hexagonal end of the valve stem. After the valve parts are assembled on the stem as previously described the boss 93' is crimped inwardly at opposite points as at 112 (Figure 16) to thus lock the main valve parts against rotation with respect to the valve stem after assembly.

It will be evident that the alternative means just described will protect the screw threaded connection of the valve stem with the nut 90, particularly when using the valve stem to thread the valve seat 74 into and from its bushing 64.

As in the preferred embodiment of the invention, guide wings 114 are employed on the upper surface of the top valve part 92, these wings serving to properly guide the main valve through the opening in the valve seat ring.

The valve seat ring is equipped with opposite pairs of upwardly extending ears 116 (Figure 9). These ears serve to center or control the movement of the outer or drain valve member ends 118 of a slidable yoke 120, the ends of this yoke being retained against complete displacement by cotter pins 122 which extend between the ears 116 above the valve member ends 118 of the yoke 120. The lower faces of the ends of the yoke are ground to form drain valve faces which engage against washers 84 to close the drain passages in the same manner as described in connection with the principal embodiment of the invention. The center of the yoke has a hexagonal opening therethrough as shown at 124 (Figure 10) and this opening fits around the hexagonal sleeve 101 which is loosely mounted on the hexagonal portion of the valve as previously described.

When the main valve is closed, the upwardly extending boss 93 on the top of the upper valve part contacts the drain valve yoke 120 and thus lifts the drain valve members on the opposite ends of the yoke above the valve seat and the rubber washers 84, as shown in Figure 8. When the valve stem is moved downwardly to displace the main valve member from its seat, the removal of the upper ends of the boss 93 from beneath the drain valve yoke 120 permits the latter to drop by gravity against the washers 84 and thus to close the drain outlets. Subsequent downward movement of the valve stem brings the collar 100 against the top of the yoke 120 as shown in Figure 9, thus forcing the yoke downwardly and the valve member faces on the opposite ends of the yoke into intimate contact with the corresponding valve faces on the upper surface 82 of the valve seat ring, compressing the rubber washers until firm metal-to-metal contact is had. The contact just mentioned serves to limit the opening movement of the main valve.

As in the case of the principal embodiment of

the invention, the valve seat ring may be removed from the surrounding bushing and taken from the barrel of the hydrant as a part of the valve assembly, by simply applying a wrench to the valve stem and turning it in an unthreading direction. By reason of the hexagonal connection between the main valve stem and the yoke 120, and the arrangement of the outer ends of this yoke between the ears 116 which are integral with the valve seat ring, the latter will be turned and unthreaded from the bushing 64 when the main valve stem is operated by a wrench. As in the case of the principal embodiment, the main valve assembly may be shipped, installed, removed for repair and replaced all as a unit.

It will be noted that the nut 90 has a bottom closed projecting portion 90' which seals the lower end of the valve stem against leakage.

The construction of the main valve parts, while of the utmost simplicity, is well adapted for preventing loosening of the valve stem from the main valve parts. In the embodiment of Figure 8, the lower valve part 90 can be screwed upwardly on the threaded lower end 96 of the valve stem to compress the packing against the upper valve part 92. During this threading movement, the upper valve part turns until it is displaced far enough upwardly to be in wedging contact with the lower end of the hexagonal sleeve 101, the corners of which bear against the upper face of the boss 93. Further tightening of the lower valve part or nut 90 wedges the upper valve part firmly against the sleeve 101. By reason of the direct connection between the valve stem and the top valve part either in the form of the set screw 108 or the crimps 112 (Figure 16), the threads on the lower end of the valve stem where they connect with the nut 90 are protected during turning movements of the valve stem. These threads are protected when the valve stem is turned to unthread the valve seat ring 74 from its bushing 64, the turning force of the wrench being transmitted directly to the valve seat ring and not through this threaded connection.

It will be apparent that we have provided main valve designs of pronounced simplicity, which insure proper drainage from the hydrant, yet effective closing and sealing of said drainage passages when the main valve is opened. It will likewise be apparent that the designs disclosed are of pronounced usefulness in removing the valve assembly as a unit, with adequate protection against injuring any of the connections of the main valve while using the valve stem in removing or installing the hydrant valve seat.

It will also be noted that in all of the embodiments herein, no stop is required in the interior of the hydrant shoe to limit the movement of the main valve, thus leaving a clear water way through the shoe to the valve seat. The valve stem and associated parts may be of any polygonal or elliptical cross section to prevent turning of the valve stem during normal operation and to impart turning movement, when desired, to the removable valve seat.

Throughout the embodiments herein, the valve seat ring and companion bushing are made of non-ferrous metal and are connected by straight threads, to facilitate their separation.

This application is a continuation-in-part of our earlier filed application Serial No. 718,752 referred to. The embodiment of Figure 1 of that application, as far as the main hydrant valve is concerned, is included herein, being disclosed in Figures 1-7 of the present application. Figures

8-16 of the present application disclose a similar design of hydrant valve.

We claim:

1. A fire hydrant comprising a barrel, an annular non-ferrous bushing fixed in the lower end of said barrel, said bushing having an inner face formed by a vertical wall and a drain outlet extending through said bushing from said face to the exterior of the hydrant, means defining an upwardly facing shoulder at the lower end of said bushing, an annular, non-ferrous valve seat ring having an exterior vertical face positioned within said bushing and seating on said shoulder, said faces having cooperating straight threads to secure said ring in said bushing, one of said vertical faces having an annular groove therein to deliver drain water from the interior of the hydrant to said drain outlet, one of said faces having a pair of spaced annular recesses therein, deformable sealing rings in said recesses of a normal cross-section different from the cross-section of the recesses, one recess being above and one below said groove, said seat ring having a drain passage comprising vertical and horizontal portions leading from an inner surface thereof to said groove, said inner surface around said passage comprising a drain valve seat, a drain valve member mounted on said stem and positioned above said drain valve seat, said seat ring having a downwardly tapered main valve seat, a main valve stem in said barrel, a main valve member carried by the lower end of said stem to engage said main valve seat upon upward movement of said main valve member, said stem being non-circular in cross-section, a yoke for imparting rotation to said seat ring to remove it from said bushing comprising a pair of arms connected to said seat ring, and a central hub, said hub having an opening embracing said stem and of the same non-circular contour as said stem, and means on said stem for urging said drain valve member against said drain valve seat to close said drain passage upon downward movement of said stem to open the main valve.

2. In a fire hydrant, a body provided at its inner end with interior threads for the attachment of a seat ring, a valve stem in said body having a main valve member on its inner end, a main valve seat ring mounted on said stem outwardly of said valve member comprising an annular portion and a central hub connected by a plurality of radial arms, said hub having a non-circular opening through which said stem extends and said stem being of corresponding non-circular form where it passes through said opening, said seat ring having a central opening defined by a main valve seat and being threaded on its exterior surface which threads are adapted to coact with the threads on the body, whereby said stem may serve to thread said seat ring in said body, said hub having an outer face constituting a drain valve seat, at least one of said arms having a drain passage therethrough which traverses said seat ring from the outer face of said hub and registers with a drain outlet leading to the exterior of the hydrant, a drain valve member on said stem, and means on said stem to operate said drain valve member to open said drain passage upon movement of said stem to close the main valve.

3. A construction in accordance with claim 2 wherein said seat ring has a lower tapered valve seat and an annular guiding surface for said valve member above said seat, and wherein said main valve member has a tapered face to engage

said seat and guiding means to enter and engage the guiding surface of said seat ring to center the tapered face of said valve member against its seat.

5 4. A construction in accordance with claim 2 wherein said drain valve member comprises a plate mounted on said stem above said hub, said plate having a non-circular opening therethrough which embraces said non-circular stem to prevent rotation of said plate on said stem.

10 5. A construction in accordance with claim 2 wherein said drain valve member comprises a plate mounted on said stem above said hub, and wherein there is a collar on said stem spaced above said plate to contact the latter when said valve stem is moved downwardly, said collar serving to seal said plate against said drain valve seat and to limit the degree of opening of the main valve.

15 6. In a fire hydrant, a body provided at its inner end with interior threads for the attachment of a seat ring, a valve stem in said body having a main valve member on its inner end, a main valve seat ring mounted on said stem outwardly of said valve member comprising an annular portion and a central hub connected by a plurality of radial arms, said hub having a non-circular opening through which said stem extends and said stem being of corresponding non-circular form where it passes through said opening,

20 30 said seat ring having a central opening defined by a main valve seat and being threaded on its exterior surface which threads are adapted to coact with the threads on the body, whereby said stem may serve to thread said seat ring in said body, said hub having an outer face constituting a drain valve seat, at least one of said arms having a drain passage therethrough which traverses said seat ring from the outer face of said hub and registers with a drain outlet leading to the exterior of the hydrant, the outer face of said hub having a smooth valve surface around the opening therein of said drain passage and being counter-bored around said opening, a resilient washer in said counter-bore which extends

35 40 45 beyond said smooth valve surface, a drain valve member comprising a plate having a smooth under surface mounted on said stem beyond said hub, said stem having spaced inner and outer abutments thereon respectively to lift said plate to open the drain valve when the main valve of the hydrant is closed, and to seal said under surface of said plate against the corresponding surface on said hub by sealing compression of said washer when the main hydrant valve is fully opened.

50 55 60 7. In a fire hydrant, a body provided at its inner end with interior threads for the attachment of a seat ring, a valve stem in said body having a main valve member on its inner end, a main valve seat ring mounted on said stem outwardly of said valve member comprising an annular portion and a central hub connected by a plurality of radial arms, said hub having a non-circular opening through which said stem extends

65 60 65 and said stem being of corresponding non-circular form where it passes through said opening, said seat ring having a central opening defined by a main valve seat and being threaded on its exterior surface which threads are adapted to

70 75 70 75 coat with the threads on the body, whereby said stem may serve to thread said seat ring in said body, said hub having an outer face constituting a drain valve seat, each of said arms having a drain passage therethrough extending from spaced inlets in the outer face of said hub, said

seat ring having a connecting outlet passage therethrough leading to the exterior of the hydrant, a drain valve member comprising a plate mounted on said stem overlying the inlets to said passages, said plate having a non-circular opening therein where it embraces said stem to maintain said plate in overlying relation with respect to said inlets, said stem having an abutment thereon to engage said plate and lift it above said inlets when the main valve of the hydrant engages its seat, said abutment being positioned on said stem to release said plate to close said inlets when the main valve of the hydrant is moved from its seat.

8. The structure defined in claim 1 in which the valve member comprises top and bottom parts with valve seat packing held between them, said parts having cooperating engaging means which lock them against relative turning movement with respect to one another around the axis of the valve stem, said bottom part comprising a nut threaded onto the lower end of said stem, said top valve part having an opening therethrough and fitting over the valve stem above its threaded end, and including means for locking said top valve part to said stem.

9. The structure defined in claim 1 in which the valve stem above said valve member is non-circular in cross section and said valve member comprises top and bottom parts, said top part having an opening therethrough to receive the valve stem, said bottom part comprising a nut threaded on the lower end of said valve stem, there being valve packing means secured between said top and bottom valve parts, and including a collar on said valve stem spaced above said main valve member and a sleeve loosely mounted on said stem between said collar and said top part to limit the movement of the latter along said stem when said lower valve part is screwed onto said valve stem, said sleeve being of similar non-circular contour to fit on said valve stem, and said yoke connects said sleeve and said valve seat ring to impart turning movement thereto from said stem in order to remove said ring from said barrel.

10. The structure defined in claim 1 in which the lower end of the valve stem is circular in cross section and the valve member comprises top and bottom parts with valve seat packing

held between them, said parts having cooperating engaging means which lock them against relative turning movement with respect to one another around the axis of the valve stem, said bottom part comprising a nut threaded onto the lower end of said stem, said top part having a circular opening therethrough and fitting over the lower end of said stem above its threaded end, and including a set screw extending through said top valve part and into said stem to lock said top valve part thereto.

11. The structure defined in claim 1 in which the valve stem is polygonal in cross section and the valve member comprises top and bottom parts with valve seat packing held between them, said parts having cooperating engaging means which lock them against relative turning movement with respect to one another around the axis of the valve stem, said bottom part comprising a nut threaded onto the lower end of said stem, said top valve part having an opening therethrough and fitting over the valve stem above its threaded end, and said top valve part having a cylindrical boss surrounding said stem and being crimped inwardly at spaced points against a plurality of the side faces of said stem to lock said top valve part thereto.

ROBERT H. MUELLER.
EARL E. CLINE.
